UNITED STATES PATENT OFFICE.

GRIFFITH JOHN, OF YONKERS, NEW YORK, ASSIGNOR TO OTIS ELEVATOR COMPANY,
OF JERSEY CITY, NEW JERSEY, A CORPORATION OF NEW JERSEY.

ROPE-DRIVE ELEVATOR.

1,102,514.

Specification of Letters Patent.

Patented July 7, 1914.

Application filed March 20, 1908. Serial No. 422,261.

To all whom it may concern:

Be it known that I, GRIFFITH JOHN, a subject of the King of Great Britain, residing in Yonkers, in the county of Westchester and State of New York, have invented 5 a new and useful Improvement in Rope-Drive Elevators, of which the following is a specification.

My invention relates to frictional rope 10 drive apparatus, and is particularly adapted to rope drive or traction elevators.

The object of my invention is the provision of simple and efficient means for moving a load through flexible power transmitting means.

A further object of the present invention 15 is the provision of a rope drive elevator system by which the frictional engagement between the driving member and the flexible 20 power transmitting means will be increased when the load in the car increases.

Other objects of the invention will appear hereinafter, the novel combinations of 25 elements being set forth in the appended claims.

The accompanying drawing illustrates the 30 application of my invention, and shows diagrammatically an electric operating system controllable from the car; but it should be understood that either electric or any other power may be used, and the controlling 35 system may be varied as desired. In this instance I have shown an electric motor M, to the shaft S of which is connected a driving sheave or drum D.

C designates the car, and W the counter-weight.

Mounted on the overhead beam 1 is a sheave 2, from which extends the rope or 40 ropes 3 which are connected at one end to the suspended sheave 4 and at the other end to the upper end of the counterweight W. Another rope or set of ropes or cables 5 are connected at one end to the car C, and 45 at the other end to the counterweight W, these cables passing upwardly from the car C over the suspended sheave 4, thence downwardly on the under side of the driving sheave or drum D, and finally upwardly to the counterweight W. If desired, instead of 50 having two sets of ropes 3 and 5, there may be only one set of ropes, one end of which is connected to the car and the other to the suspended sheave 4, the counterweight 55 W being connected to the ropes between

the sheave 2 and the right-hand side of the driving sheave or drum D.

6 designates controlling apparatus comprising reversing switches, accelerating mechanism, etc., which is controlled by the 60 manual switch 7 in the car such that when the switch 7 is moved to one position, the motor M will operate the power transmitting connections to move the car upwardly, and when the switch is moved to another 65 position the car will be moved downwardly. Although the counterweight may be proportioned with respect to the car and the load as desired, it is preferred that it be such that the tension on the lead 8 will be 70 substantially equal to the tension on the lead 9 when an average load is in the car C. It is evident that when the car and its load exerts a certain tension on the ropes 75 3 and 5, tension will be transmitted to the lead 9 and twice this tension will be transmitted to the lead 8. The counterweight W should therefore be such as to relieve this tension on the lead 8 to a sufficient extent so as to make it substantially the same as 80 that on the lead 9 for an average load. Now, when the load in the car is increased, the tension on the lead 9 will be increased in direct proportion thereto, but the increase in tension on the lead 8 will be twice 85 as great. The load in the car may be increased, however, until the tension on one of the leads is considerably greater than the tension on the other lead before any slipping takes place. 90

I am aware of the system of rope drive for elevators invented by Michael E. Neenan, and covered in his application for Letters Patent, Serial No. 365,705, filed April 1, 1907, for an improvement in elevators, but 95 I regard my arrangement as an improvement thereover in lessening the number of sheaves. In the Neenan construction referred to there are two sheaves on fixed bearings and one mounted on the counterweight besides the driving sheave, the driving ropes extending from the car upwardly over the overhead sheave, downwardly under the counterweight sheave, thence upwardly over another overhead sheave, thence 100 downwardly under the driving sheave, and finally upwardly to the counterweight. In my arrangement the sheave on the counterweight is eliminated.

Obviously those skilled in the art may 110

make various changes in the details and arrangement of parts without departing from the spirit and scope of my invention, and I desire therefore not to be limited to the precise construction disclosed.

Having thus fully described my invention, what I claim and desire to have protected by Letters Patent of the United States is:—

1. The combination with a load carrying device, of a motor, and power transmitting means comprising a cable, a weight connected to said cable, a traction driving sheave or drum and only two additional sheaves, and a stationary support for one of said additional sheaves, the other of said additional sheaves being suspended from the cable and supporting the load carrying device.

2. In an elevator, the combination of a car, a motor, a driving sheave or drum, flexible power transmitting means connected to the car and associated with said driving sheave, a weight connected to said means, and only two additional sheaves associated with said means, one of said additional sheaves being carried by said power transmitting means and carrying the car.

3. In an elevator, the combination with a car, of a motor, a driving drum, a single sheave mounted on fixed bearings, a loose sheave, a weight, a rope or ropes associated with said first named sheave and connected at one end to said loose sheave and at the other end to the weight, and an additional rope or ropes connected at one end to the car and at the other end to said weight, with its intermediate portion associated with said loose sheave and said driving drum.

4. In an elevator, the combination with a car and a counterweight, of a motor, a sheave journaled in stationary bearings, a driving drum connected to the motor, a loose sheave, flexible power transmitting means connected to the car, counterweight, and said loose sheave, said power transmitting means extending upwardly from the car

over said loose sheave, downwardly under the driving drum, and upwardly from the counterweight over the fixed sheave to the loose sheave.

50

5. In an elevator, the combination with a car, of a motor, a driving sheave, a flexible member forming a direct connection between said car and one side of said sheave, a movable pulley with which said flexible member 55 engages, a connection between said pulley and the other side of said driving sheave, and a weight for reducing the tension of the lead on said other side of the driving sheave.

6. In an elevator, the combination with a car, of a motor, a driving member, a rope or ropes connected to the car and associated with said driving member, a weight connected directly to one of the leads extending from said driving member, a single sheave 60 affording a direct connection between the car and the other lead extending from said driving member, a rope connected between said sheave and said weight, and a single sheave associated with said rope.

65

7. In an elevator, the combination with a car, of a motor, controlling apparatus for said motor, a driving drum or sheave connected directly to the motor shaft, an overhead sheave mounted on stationary bearings, 75 a loose sheave, a weight, a rope or ropes connected at one end to said loose sheave to suspend the same and at the other end to said weight, the intermediate portion of said rope extending over the overhead sheave, 80 another rope or ropes connected at one end to the car and at the other end to said weight, with its intermediate portion extending over said suspended sheave and under said driving sheave.

70

In testimony whereof, I have signed my name to this specification in the presence of two subscribing witnesses.

GRIFFITH JOHN.
